WORK HOLDER FOR A MACHINE TOOL

Robert F. Moyer, Warwick, R. I., assignor to Standard Die Set Manufacturers, Inc., Cranston, R. I., a corporation of Rhode Island

Application April 16, 1956, Serial No. 41,079

Term of patent 14 years

(Cl. D54—14)

Fig. 1.

Fig. 2.

Fig. 3.

Fig. 1 is a perspective view of a work holder for a machine tool showing my new design;

Fig. 2 is a bottom plan view thereof;

Fig. 3 is an elevational view of the work holder or fixture for machine tools.

I claim:

The ornamental design for a work holder for a machine tool, substantially as shown.
